UNITED STATES PATENT OFFICE.

CHARLES D. McDONALD, OF CHICAGO, ILLINOIS, ASSIGNOR TO McDONALD MACHINE CO., OF CHICAGO, ILLINOIS, A CORPORATION OF ILLINOIS.

AUTOMATIC DIE-PRESS STOPPING MECHANISM.

Application filed August 8, 1927. Serial No. 211,369.

This invention relates to automatic die press stopping mechanism and its principal object is to provide improved pneumatically operated mechanism for holding the hand lever of the press starting and stopping mechanism in operative or starting position and for releasing said hand lever and thereby stopping the press in case an abnormal condition arises in any of the passage ways through which the work moves. Part of the subject matter disclosed in this application has been continued from a co-pending application for patent on automatic die press stopping mechanism filed by me in the United States Patent Office on February 11, 1927, under Serial No. 167,412.

The present invention has reference more particularly to an automatic die press in which strips of material are inserted, one at a time from a stack of strips, into a feed way and therein fed in a step by step manner to the dies of the press, where the strips are operated upon, either by blanking out pieces therefrom, or otherwise as is well understood, the blanked out pieces being discharged through a discharge chute and delivered to other mechanism for subsequent operation. Occasionally more than one strip of material is accidentally inserted into the feed way, in which case it becomes necessary to stop the press and extract the superfluous strip, and one of the objects of the present invention is to provide improved pneumatic means for releasing the starting and stopping lever of the press in case of such an emergency, whereby the press will be automatically stopped. Sometimes the blanked out articles pile up in the discharge chute, which makes it necessary to stop the press and relieve the congestion and one of the objects of the present invention is to provide improved pneumatic means for releasing the starting and stopping lever in case of such an emergency to thereby automatically stop the press.

With these and other objects and advantages in view, this invention consists in automatic press stopping mechanism embodying a pneumatically operated member for holding in starting position the hand lever or starting and stopping lever of press starting and stopping mechanism; said mechanism also embodying means located at the passage

ways for the work, for opening an air vent 55 and admitting air, at atmospheric pressure, to said pneumatically operated member, whereby the hand lever or starting and stopping lever is released and permitted to fall, thereby releasing the usual clutch and applying the usual brake of the press. The invention further consists in a vacuum head having a suction end arranged to contact with the hand lever of the press starting and stopping mechanism whereby said hand lever is held in operative or starting position so long as vacuum is maintained in the suction end of the head, together with means located at the feed way or other passage way for the material and operating to release the vacuum in the vacuum head when an emergency occurs in said feed way or other passage way. The invention further consists in a vacuum head having a suction end arranged to contact with the hand lever of the press starting and stopping mechanism and means for releasing the vacuum in said vacuum head, which means are controlled by the number of strips which enter the feed way at one time 75 or the number of blanked articles that pass through the discharge chute. The invention further consists in the several novel features of construction, arrangement and combination of parts hereinafter fully set forth 80 and claimed.

The invention is clearly illustrated in the drawings accompanying this specification, in which:

Fig. 1 is a side elevation of an automatic die press partly broken away and stripped of much of the press mechanism and showing a simple embodiment of the present invention applied to the hand lever of the starting and stopping mechanism; Fig. 2 is a view, partly in side elevation and partly in central longitudinal section, of the vacuum head and a fragment of the hand lever. Fig. 3 is a view of the feed table and associated parts and showing one of the vacuum release means employed in connection with the feed way, the view being taken in the direction of the arrow 3 in Figs. 1 and 4; Fig. 4 is a detail vertical cross section taken on the line 4—4 of Fig. 3; Fig. 5 is a fragmental vertical section taken through the discharge chute; Fig. 6 is a side elevation of the vacuum release mechanism associated 100

105

with the discharge chute and Fig. 7 is a vertical section taken on the line 7—7 of Fig. 6.

Referring to said drawings, which illustrate a simple embodiment of the present invention applied to an automatic die press of conventional form, the die press body is seen at 10 and said body supports the various operating mechanisms of the die press. 10 A press of the type illustrated is more fully shown and described in my prior Patents No. 1,252,278, dated January 1, 1918, and No. 1,529,031, dated March 10, 1925, to which reference is made herein. As is well understood presses of this type are equipped with clutch mechanism 23, whereby a continuously rotating drive pulley (not shown) may be operatively connected and disconnected from the crank shaft 21 which operates the ram 20 22 of the press. The presses are also equipped with brake mechanism 23^a for applying a braking action to said crank shaft whenever the clutch is disconnected. As in my prior patents above referred to the combined clutch and brake mechanism is controlled from a hand lever 11, fulcrumed upon the press body at 12 and connected to the clutch and brake mechanism by a link 14, an operating strut 13 and links 15, 16, as is well understood. These parts are so proportioned and arranged that when the hand lever is in its upper or starting position wherein the press operates, the center line between the ends of the link 14 has not 30 passed the fulcrum 12 of the hand lever 11 whereby whenever said hand lever is released from its operative or starting position as shown in Fig. 1, it may fall by gravity, thereby actuating the clutch and brake mechanism to disconnect the clutch and apply the brake and consequently stop the press.

At the side of the press body opposite the one seen in Fig. 1 is the feed table 17 of the press. Said feed table has a feed way 18 in its upper side through which the strips of material *a*, are fed to the dies 24, 25. The feed way 18 is located between the top member 19 of the table and a bar or plate 20 (see Figs. 3 and 4) and finger bar mechanism (not shown) is mounted in a guide way in the feed table and is arranged to feed the strips of material towards the dies 24, 25, in a step by step fashion as is well understood.

Secured upon the side of the press body adjacent the hand lever 11 is a vacuum head 32, which contains an air passage or conduit 33 that leads from its suction end 36 to a 60 vacuum pipe 34. The vacuum pipe leads to a suitable source of vacuum supply, and in case the press is provided with a vacuum pump it may lead thereto, otherwise it may lead to a vacuum tank 35 connected with 65 a suitable vacuum pump (not shown).

When an independently operated vacuum pump and vacuum tank are used, the main vacuum line 35^a from the vacuum tank may lead to the strip lifters with which presses of this type are equipped and said vacuum pipe 34 may lead to any of the other pneumatically operated devices of the press. The suction end of the vacuum head is provided with a resilient suction cup or suction pad 37 which is arranged to contact with a disc like 70 part 38 of the hand lever whereby when a partial vacuum is created in said suction end of the vacuum head the hand lever will be held against its suction end until the vacuum is released in the vacuum head or 75 the lever forcibly disconnected therefrom. In the conduit or air passage 33 is a spring pressed valve 39 which is adapted to seat upon a valve seat 40 in the conduit 33 and thereby close the passage through said conduit and said valve 39 is mounted upon a valve stem 41, which may protrude from the suction end of the vacuum head. The part 38 of the hand lever engages with said valve stem 41 whenever the hand lever is 80 raised to its starting or operative position, whereby the valve is unseated and the passage from the vacuum pipe 34 to the suction end is thereby opened. When the hand lever is released from the vacuum head, the valve 85 39 closes the passage through the vacuum head and prevents any leakage of air at this point. A coiled compression spring 90 behind the valve operates to seat it upon its seat whenever the hand lever is moved 100 away from the valve stem 41. It will be observed that so long as a vacuum extends to the suction end of the vacuum head the hand lever will be effectively held in its starting or operative position, but that in case the 105 vacuum in said suction end of the vacuum head is released, the hand lever will be permitted to fall and thereby actuate the clutch and brake mechanism to stop the press. 110 Leading away from the conduit or air passage 33 is a vent tube 42 which has branches connected with vacuum release mechanisms which are set in operation whenever an abnormal condition arises in the feed way or in the discharge chute or any other vulnerable spot in the press where such vacuum release mechanism is located.

The vacuum release device or trip device (so called in my co-pending application above referred to) which is operated by a superfluous number of strips entering the feed way 18 is shown in Figs. 3 and 4 and comprises a trip pin 51 slidably mounted in a guide sleeve 52, which is formed with a part 115 53 that is bolted or otherwise secured to one of the brackets 54, which carries the strip lifting and inserting mechanism (not shown) of the press. Said part 53 of the guide sleeve 52 has a bracket arm 55 extending therefrom upon which is secured an air 120 125 130

valve or vent device 56 that is connected to the main vent tube 42 by a branch vent tube 42^b. The trip pin 51 engages with a throw amplifying lever 57 fulcrumed upon the bracket arm 55 and the long arm of said lever 57 engages with the valve stem 58 of the air valve or vent device 56. As a preference an adjustment screw 59 is threadedly secured in the lever 57 and contacts with the end of the trip pin 51 and furnishes adjustment means for affording a close adjustment between the lever 57 and trip pin 51. The extent of movement of the long arm of the lever 57, (which engages with the valve stem) is considerably greater than the extent of movement of that part of the lever which is engaged by the trip pin 51, whereby slight movement of the trip pin (such as is caused by more than one thickness of material passing under the trip pin) will cause a relatively long movement of the outer end of the lever 57, the extent of such movement being sufficient to open the air valve or vent device 56, and admit air to the vent tube 42.

As has been explained the strips of material are fed one at a time to the dies 24, 25, where the articles are blanked out of the strips. Said articles fall upon a discharge chute 26 which conveys them to other mechanisms for subsequent treatment. The discharge chute usually in the form of a trough like device, and at a place adjacent the receiving end of the discharge chute is a pivotally mounted trip member 27 under which the stamped out articles pass on their way to the discharge end of the discharge chute. The trip member may be in the form of a strip or bar of material mounted upon a rock shaft 28 which is journaled in brackets secured to the sides of the discharge chute. Sufficient clearance is left between the lower end of the trip member 27 and bottom of the discharge chute to permit the blanked out articles to pass freely, one at a time, under the trip member. However, in case the articles pile up in the discharge chute after leaving the dies they swing said trip member upward slightly and cause a valve or vent device 29 in the branch 42^b of the vent tube 42 to be opened, thereby breaking the vacuum in the suction end of the vacuum head 32 and permitting the hand lever 11 to fall and stop the press. As illustrated in the drawings, the rock shaft 28 of the trip member 27 has a counterbalanced arm 30 secured to it, which arm carries a valve member 31 which normally closes a small opening in the vent device 29 of the vent tube 42^b. When, however, the trip member 27 is swung upward, the arm 30 is consequently moved in a direction to unseat the valve member 31 from the vent opening in the vent tube device 29 thereby permitting air to rush in and break the vacuum in the suction end of the vacuum tube.

In the operation of the automatic press stopping mechanism above described the hand lever 11 is manually raised into contact with the suction end of the vacuum head 32 as seen in Figs. 1 and 2, thereby throwing the clutch and brake mechanism into the position wherein the press is started. During normal conditions in the feed way and in the discharge chute, the press continues to run, but in case more than one strip of material is inserted into the feed way 18, the trip pin 51 is thereby raised, the air valve or vent device 56 thereby opened, air admitted through the branch 42^b and vent tube 42 to the suction end of the vacuum head 32, the vacuum in said end is released and the hand lever falls, thereby actuating the clutch and brake mechanism to stop the press. The attendant thereupon removes the superfluous strip and starts the press again by moving the hand lever up into engagement with the vacuum head. In case the blanked out articles pile up in the discharge chute the trip member 27 is raised and the vent opening in the end of the vent tube 42^b is thereby uncovered, permitting air to enter the vent tube 42 and break the vacuum in the suction end of the vacuum head, consequently permitting the hand lever to fall and stop the press as before. The attendant then relieves the jam in the discharge chute and lifts the hand lever as before to start the press.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. Automatic die press stopping mechanism for die presses having a passage way for the work, comprising in combination, the hand lever of the press starting and stopping mechanism, a vacuum head having a suction end engaging said hand lever whereby said hand lever is supported in its raised or starting position when vacuum is created in the suction end of said vacuum head, said vacuum head being connected to a source of vacuum supply, a vent tube leading from said vacuum head and having an air vent therein, and a normally inactive trip device for opening said air valve, which trip is made operative under an abnormal condition arising in said passage way.

2. Automatic die press stopping mechanism for die presses having a passage way for the work, comprising in combination, the hand lever of the press starting and stopping mechanism, a vacuum head having a suction end engaging said hand lever whereby said hand lever is supported in its raised

or starting position when vacuum is created in the suction end of said vacuum head, said vacuum head being connected to a source of vacuum supply, a vent tube leading from said vacuum head and having an air vent therein, and a normally inactive trip device for opening said air vent and having a pivoted vent actuating member capable of being moved by a plurality of pieces of the work.

3. Automatic die press stopping mechanism, comprising in combination, the hand lever of the press starting and stopping mechanism of a die press having a strip feed way, a vacuum head having a suction end arranged to contact with said hand lever, whereby the lever is supported in starting position when vacuum is created in the suction end of said vacuum head, said vacuum head being connected with a vacuum source, a vent tube leading from the suction end of said vacuum head and having an air valve thereon, a normally inactive trip device associated with the strip feed way of the press and having a valve actuating member operating to open said air valve when an abnormal condition arises in the feed way.

4. Automatic die press stopping mechanism for presses having a strip feed way, comprising in combination, the hand lever of the press starting and stopping mechanism, pneumatic means engaging said hand lever whereby said hand lever is supported in its raised position when vacuum is created in said pneumatic means, a vent tube leading from said pneumatic means and having an air valve thereon, and a normally inactive trip device for actuating said air valve, which trip device is made operative under an abnormal condition arising in the strip feed way of the press.

5. Automatic die press stopping mechanism, comprising in combination, the hand lever of the press starting and stopping mechanism of a die press having a strip feed way, a vacuum head having a suction end arranged to contact with said hand lever, whereby the lever is supported in starting position when vacuum is created in the suction end of said vacuum head, said vacuum head being connected with a vacuum source, a vent tube leading from the suction end of said vacuum head and having an air valve thereon, a normally inactive trip device associated with the strip feed way of the press and having a throw amplifying lever operating to open said air valve when an abnormal condition arises in the feed way.

6. Automatic die press stopping mech-

anism comprising in combination, the hand lever of the press starting and stopping mechanism of a die press having a strip feed way, a vacuum head having a suction end arranged to contact with said hand lever, whereby the lever is supported in starting position when vacuum is created in the suction end of said vacuum head, said vacuum head being connected with a vacuum source, a vent tube leading from the suction end of said vacuum head and having an air valve thereon, a normally inactive trip device associated with the strip feed way of the press and having a trip pin extending into the feed way and a throw amplifying lever engaging said pin and operating to open said air valve when an abnormal condition arises in the feed way.

7. Automatic die press stopping mechanism, comprising in combination, the hand lever of the press starting and stopping mechanism of a die press having a strip feed way, a vacuum head having a suction end arranged to contact with said hand lever, whereby the lever is supported in starting position when vacuum is created in the suction end of said vacuum head, said vacuum head being connected with a vacuum source, a vent tube leading from the suction end of said vacuum head and having an air valve thereon, a normally inactive trip device associated with the strip feed way of the press and having a trip pin extending into the feed way and engaged by a superfluous number of strips passing under the pin, and operating to open said air valve when an abnormal condition arises in the feed way.

8. Automatic die press stopping mechanism, comprising in combination, the hand lever of the press starting and stopping mechanism of a die press having a strip feed way, a vacuum head having a suction end arranged to contact with said hand lever, whereby the lever is supported in starting position when vacuum is created in the suction end of said vacuum head, said vacuum head being connected with a vacuum source, a vent tube leading from the suction end of said vacuum head and having an air valve thereon, a normally inactive trip device associated with the strip feed way of the press and having a trip pin extending into the feed way and engaged by a superfluous number of strips passing under the pin, and a throw amplifying lever engaged by said pin and operating to open said air valve when an abnormal condition arises in the feed way.

CHARLES D. McDONALD.
